CALENDAR RACK

Robert J. Higginbotham, Salisbury, and Carl M. Martin, Winston-Salem, N. C., assignors to Carl M. Martin and Luther E. Martin, both of Winston-Salem, N. C.

Application March 31, 1933, Serial No. 663,752

9 Claims. (Cl. 19—162)

This invention relates to an improved calendar rack which has many features not heretofore present in calendar racks.

Some of the improvements and results obtained by the improved calendar rack are: the number of split laps is reduced to a minimum; soft and fluffy laps are prevented; waste is reduced by the production of a firm and even lap; the breakage of pinions, lap rolls, necks and the like is eliminated; free and easy turning of lap pin and rollers is assured; requires the addition of lubricant only at long separated periods; oily and greasy laps are eliminated; labor is saved and production is increased; the calendar rack 5 head will follow worn or irregular lap pin necks; pressure on lap pin neck is released when friction mechanism binds, or gears become clogged; the pressure applying means is moved vertically upward a short distance when a shearing pin is 10 broken and not in the arc of a circle as heretofore has been the case in other structures and thus breakage of laps prevented as the lap pin is still held in position and continues to receive the lap until the machine can be stopped to remedy the fault.

It is a well-known fact that in textile mills the stock is run through picking machinery to cleans the stock and to produce a lap of uniform thickness. The lap emerging from the 15 picker is very fluffy and in order to produce a compact lap or roll, the lap is wound onto a lap pin. The lap pin is pressed against the lap by calendar racks engaging the lap pin at both ends, which calendar racks are geared to a common shaft, the turning of which is retarded by a friction drum, weight and lever. Sometimes 20 the train of gears between the calendar racks and the friction drum becomes choked or excessive friction is applied to the drum and in either instance the pressure applied by the lap pin on the calendar racks becomes too great and results in breakage of the calendar racks or other parts of the machine. In the improved 25 calendar rack hereinafter explained more fully this breakage is prevented by the provision of shearing means associated with pressure applying means on the calendar rack, with the pressure applying means being so arranged as to allow the lap pin to move freely upward a short distance when the shearing occurs.

Some of the objects of the invention having been stated, the details of the invention will appear more fully in the description hereinafter following, when taken in connection with the accompanying drawing, in which—

Figure 1 is a side elevation of the improved calendar rack with the lower central portion thereof broken away;

Figure 2 is an elevation, looking at the right hand side of Figure 1;

Figure 3 is a transverse sectional view, taken along the line 3—3 in Figure 1;

Figure 4 is an isometric view, partly in section, of one of the rollers in the calendar rack;

Figure 5 is an enlarged detail of the lubricant-retaining feature as seen in the upper left hand portion of Figure 4.

Referring more specifically to the drawing, the numeral 10 designates an upright rack having teeth 11 on the lower portion thereof, a portion 20 of the lower half being broken away. The teeth 11 are for engagement with the usual gears or pinions. A head 12 is loosely mounted on the rack for vertical sliding movement when undue pressure is applied upwardly on the head by the 25 lap pin. The rack has opposed grooves 13 and 14 in which pins 15 and 16 loosely slide, these pins 15 and 16 being secured in the side portions 17 and 18 of head 12 in any suitable manner, such as by being threadably mounted therein. 30 The side portions 17 and 18 of head member 12 are joined together by web portion 19.

There is a goodly amount of clearance between the side portions 17 and 18 and the rack 10 in order that a certain amount of swivel 35 action may be permitted in head 12 so as to allow the head to rock or swivel on the hemispherical head of pin 20, and also to allow the rollers to remain in parallel contact with the lap pin when either of the shearing pins breaks. 40 The upper surface of web portion 19 has therein a suitable cavity in which the rounded lower end of pin 20 may have lodgment, said pin 20 being vertically disposed and slidably penetrating a suitable hole in the rack bar 10 and to permit the rollers in the head to remain in parallel 45 contact with the lap pin when either head moves upward due to breakage of a shearing pin. A suitable shearing pin 21 penetrates the rack bar 10 and the pin 20, this pin being adapted to 50

shear when undue upward pressure is exerted on the head 12 by the lap pin, the end bearing of which is designated by reference character 22. A suitable chain 23 is secured as at 24 to rack bar 10 and the other end thereof is secured as at 25 to web 19 of head 12, the purpose of this chain being to prevent the head 12 from falling further downward on the rack bar when the lap pin is removed.

10 The side portions 17 and 18 of head 12 are penetrated by pins 27 and 26, each of the pins 26 and 27 having a flattened portion 28 which is adapted to be engaged by a set screw 29 or 30 threadably mounted in side portion 17 to prevent said pins from rotating. Each of the pins 26 and 27 and the rollers associated therewith are identical except as to the size of the rollers thereon and a description of the structure shown in Figures 4 and 5 will suffice for both rollers and the structure associated therewith.

15 Each of the pins 26 and 27 has a passageway 30a having in the outer end thereof a grease nipple 31 and the inner end of the passageway communicated with the exterior of the pin intermediate the ends thereof whereby a lubricant under pressure can be applied to the interior of the roller mounted on the pin. The roller on pin 26 is designated by 32, while the roller on pin 27 is designated by 33. As the two rollers 20 are identical in structure, a description of roller 33 and associated parts as shown in Figures 4 and 5 will suffice.

25 Suitable rings 35 and 36 are fixedly secured in a centrally disposed bore extending longitudinally of the roller and the ends of rollers 37 are rotatably mounted in these rings. The outer ends of the rollers 32 and 33 have a larger bore than that in which the rollers 37 are mounted. A lubricant retaining structure is mounted 30 in each of such larger bores in the outer ends of the rollers 32 and 33. This lubricant retaining structure is first assembled and then inserted in the ends of the rollers such as 33 and secured therein by any suitable means such as 35 by pressing the lubricant retaining assembly into the end of the roller. The lubricant retaining structure comprises a circular cup-shaped member 40 into which is inserted the washer 41 made of any suitable flexible material such as 40 leather, then ring 42 is inserted on top of washer 41 and then an endless tension spring 43 is passed over the smaller end of the washer 41 to press it against pin 27 when the pin is inserted therein. Then washer 44 is placed in 45 position with the smaller portion of the washer 41 penetrating the centrally disposed hole in washer 44. Then the rim of cup-shaped member 40 is crimped or rolled to secure the parts in assembled position after which one of these lubricant retaining structures is placed in each 50 end of the rollers 32 and 33 by any suitable means or method as above described. Then the pin 26 or 27 is inserted through the roller 32 or 33 by means of a suitable pilot (not shown) 55 which spreads the washer 41 most distant from the end of the roll 32 or 33 into which the pin is first inserted.

60 Suitable ring washers 45 are placed between the oil retaining assembly and the roller bearing to protect the washers 41 and 44 from wear by the roller bearing support rings 35 and 36.

65 In the drawing and specification there has been set forth a preferred embodiment of the invention, and although specific terms are employed, 70 they are used in a generic and descriptive sense

only and not for purposes of limitation, the scope of the invention being set forth in the appended claims.

We claim:

1. In a device of the class described comprising a rack, a lap pin bearing head having one end thereof engaging the rack, means engaging the central portion of the head and being slidably mounted in the rack, and a shearing pin in the rack penetrating said means engaging the central portion of the head. 5

2. In a device of the class described comprising a rack, a lap pin bearing head having one end thereof slidably engaging the rack, a pair of rollers mounted in the head for engaging the lap pin bearing, means engaging the central portion of the head and being slidably mounted in the rack and a shearing pin in the rack penetrating said means engaging the central portion of the head. 15

20 3. In a device of the class described comprising a rack, a lap pin bearing head having one end thereof slidably engaging the rack, means engaging the central portion of the head and being slidably mounted in the rack, a shearing pin in the rack penetrating said means engaging the central portion of the head, the slidable connection between the head and the rack having a relatively wide clearance to permit lateral rocking of the head on the rack. 25

30 4. In a device of the class described comprising a rack, a lap pin bearing head having one end thereof slidably engaging the rack, a pair of rollers mounted in the head for engaging the lap pin bearing, means engaging the central portion of the head and being slidably mounted in the rack, a shearing pin in the rack penetrating said means engaging the central portion of the head, the slidable connection between the head and the rack having a relatively wide clearance to permit lateral rocking of the head on the rack. 35

35 5. In a device of the class described comprising a rack, a lap pin bearing head slidably and pivotally mounted on the rack and having lateral rocking movement with relation to the rack to follow the lap pin, a shearing pin in the rack normally preventing sliding movement of the head above a given point on the rack, and means for limiting upward movement of the head after 40 the shearing pin breaks. 50

40 6. A calendar rack having a lap pin bearing head slidably mounted thereon and having lateral rocking movement with relation to the rack to follow the lap pin, a shearing pin in the rack beyond a given point on the rack, and means for limiting upward movement of the head on the rack when undue pressure on the head breaks the shearing pin. 55

60 7. In a device of the class described comprising a rack, a lap pin bearing head slidably mounted on the rack and having lateral rocking motion with relation to the rack to allow the head to follow the lap pin, a shearing pin in the rack normally preventing sliding movement of the head above a given point on the rack, a pair of rollers mounted in the head for engaging the lap pin bearing, and means for limiting upward movement of the head on the rack when the shearing pin breaks. 65

70 8. A calendar rack having a head slidably mounted thereon and having lateral rocking motion with relation to the rack, a pin in the rack 75

engaging the top of the head, a shearing pin holding the pin in the head for preventing sliding movement of the head on the rack beyond a given point on the rack, a pair of rollers 5 mounted in the head for engaging the lap pin bearing, means for limiting upward movement of the head of the rack when undue pressure on the head breaks the shearing pin.

9. A calendar rack having a head slidably 10 mounted thereon and having lateral rocking mo-

tion with relation to the rack, a pin in the rack engaging the top of the head, a shearing pin holding the pin in the head for preventing sliding movement of the head on the rack beyond a given point on the rack, means for limiting upward movement of the head on the rack when undue pressure on the head breaks the shearing pin. 5
